UNITED STATES PATENT OFFICE

EVERETT WORTHINGTON, OF CHICAGO, ILLINOIS, ASSIGNOR TO LEROY ESCHNER, OF CHICAGO, ILLINOIS

DESIGN FOR A CIGAR AND CIGARETTE LIGHTER

Application filed July 10, 1931. Serial No. 40,483. Term of patent 3½ years.

To all whom it may concern:

Be it known that I, EVERETT WORTHINGTON, a citizen of the United States, residing at Chicago, in the county of Cook and State of Illinois, have invented a new, original, and ornamental Design for a Cigar and Cigarette Lighter, of which the following is a specification, reference being had to the accompanying drawings, forming part thereof.

of a cigar and cigarette lighter showing my design, and

Figure 2 is a perspective view of the side of a cigar and cigarette lighter showing my design.

I claim:

The ornamental design for a cigar and cigarette lighter, as shown.

EVERETT WORTHINGTON.
